AUTOMATIC NUMBERING DEVICE

Kurt Frenzel, Leipzig, Germany

Application May 23, 1934, Serial No. 727,084
In Germany May 27, 1933

13 Claims. (CL. 101—88)

This invention relates to automatic numbering devices for printing presses, in which the feed motion of the number wheels is effected by a member built into the numbering device and depressed during the printing step by the impression cylinder or the platen of the press.

The known numbering devices of this class number either forward or backward, but do not permit alternative numbering. Printers are therefore compelled to provide for two different types of numbering devices, i. e., one whose number wheels bear numbers arranged for counting forward and another one for counting backward.

The object of the invention is to provide a numbering device for printing presses, which can move forward as well as backward and which possesses, for forward and backward motion, separate or reversible control members for the transition to tens. The members serving for bringing about this transition must be double, that is, one of them must be capable of forward adjustment and another one capable of backward or forward or backward adjustments, since, when counting forward, the tens digit has to be adjusted at the transition from 9 to 0 and, during backward counting, from 0 to 9. Feed of the number wheels in two directions can be effected in different ways, e. g., by employing the method used in known numbering devices and fitting each wheel with two feed gear wheels having their teeth disposed in opposite directions and providing further two sets of pawls adapted to alternatively engage, or become disengaged from, the respective feed wheels. As in the known numbering devices transition to tens is due to a special shape of the feed wheels and pawls, both feed systems must be provided with separate feed motion for the tens owing to the fact that one system works while the other stops. The provision of two feed wheels for each number wheel and two sets of pawls would, however, involve a considerable enlargement of the numbering device, and the invention substitutes therefore for the two feed wheels a pin gear which can alternatively to the right or left of the shaft be engaged by the pawl or feed lever.

Other features of the invention serve the same purpose of providing a numbering device of compact and handy design and insuring reliable feeding.

By way of example, the accompanying drawing illustrates one form of the invention on an enlarged scale.

Figure 1 is a side view of a numbering device according to the invention; Fig. 2, a top view

thereof; Fig. 3, a section on the line A—B, of Fig. 1; Fig. 4, a view in the direction of the arrows E—F, of Fig. 1, with the cover removed; Fig. 5, a section on the line C—D, of Fig. 1; Fig. 6, a section on the line G—H, of Fig. 1; Fig. 7, a side view of a number wheel; Fig. 8, a detail view of the locking device for the number wheels; and Fig. 9, a cross section of a number wheel.

1 is a U-shaped frame whose two sides 1b form hollow bodies having two detachable walls 2 and 3. A U-shaped bow 4 is oscillatorily secured to the frame 1 by means of the screws 5 and extends parallel to the base plate 1a of the frame 1. The web of the U-shaped bow 4 extends from one side of the U-shaped frame 1 to the other. The sides 4a of the bow 4 extend through corresponding recesses into the hollow space of the frame sides 1b and terminate in forks which surround pivots of a shaft guided with flattened parts in a slot of the sides 1b of the U-shaped frame 1. The ends of the shaft 6 disposed in the hollow spaces of the sides 1b of the frame 1 carry each a slide 7. The shaft 6 is influenced by two springs 8 disposed in the hollow spaces of the sides 1b of the frame 1 and supported with one end on the bottom of the hollow spaces and with the other end upon the slide 7. The springs 8 press the shaft 6 against the plate 2 covering the hollow spaces of the sides 1b of the frame 1 on top. The guide slot for the shaft 6 in the sides 1b is so dimensioned that the shaft 6, against the action of the springs 8, can be pressed a few millimeters towards the base plate 1a of the frame 1, the parallel displacement of the shaft 6 being insured by the bow 4.

The shaft 6 carries the number wheels or discs 9, 10a, 10b, etc. forming a decagon on their circumference and bearing on their peripheral surfaces the consecutive numbers 0 to 9. The number wheel 9 represents the units; the wheel 10a, the tens; the wheel 10b, the hundreds, and so forth. The unit wheel 9 is provided on its outer face with ten pins 11 arranged on a concentric circle and extending parallel to the shaft 6. To the portion of the shaft 6 positioned between the unit wheel 9 and the nearest side 1b of the frame 1 a finger 12 is secured which is directed towards the base plate 1a of the frame 1 and projects with its free offset end behind the row of pins 11 from below. In this relatively thick offset end a ball 13 is located on the side facing the row of pins 11 and pressed against the latter by the spring 14. When the unit wheel 9 is in such a position that two faces are parallel to the base plate 1a of the

frame 1, or, in other words, in printing position, the ball 13 will engage the gap between two pins 11 and thus lock the unit wheel 9 in position. On either side of the finger 12, on the inside of 5 the adjacent side 1b of the frame 1, a two-armed lever 15 extending approximately parallel to the base plate is disposed so as to be movable about pins 16. The ends of these two levers 15, which face each other, engage a recess of the finger 12 10 carried by the shaft 6 and embrace each a pin 17 provided on the finger 12 in the said recess, so that during an upward and downward motion of the shaft 6 the ends of the levers 15 will swing about their suspension pins 16. To the free end 15 of one lever 15 a pawl 18 is articulated by means of a small screw and engages the row of pins 11. A spring 19 secured to the frame 1 presses the pawl 18 against the row of pins 11. If the shaft 6 is depressed, the pawl 18 will move in opposite 20 direction, i. e., upwardly. The lever 15 is so dimensioned that during this relative motion of the row of pins 11 and the pawl 18 the latter moves only from one pin 11 to the next. If the shaft moves up again in response to the action 25 of the springs 8, the pawl 18 will descend and thus move the unit wheel one step. As the shaft 6 and the pawl 18 move in opposite directions, the depression of the shaft 6 can be relatively slight to insure feeding. Clockwise or counter-clockwise, or forward or backward feeding of the unit wheel is effected by articulating the pawl 18 to one or the other of the levers 15. Since the pawl 18 is easily detachably secured to the levers 15 only by means of the small screw mentioned, 30 it can be readily moved from one lever to the other, according to the feed required. It is further possible to provide each lever 15 with a pawl 18, one of which will then be in operative position at a time.

40 On its side facing the tens wheel 10a the unit wheel 9 is offset like a hub, and in this offset portion a slide 20 moving in a guide is radially displaceably arranged. The slide 20 is exposed to the action of a spring wire 21, which presses it outwardly, and carries a pin 22 having preferably a square cross section. The outer end of the slide 20 projects slightly beyond the circumference of the hublike portion, and the wheel 10a possesses on the side facing the unit wheel 9 a 45 concentric annular groove 23 engaged by the pin 22. From the inner edge of the annular groove 23 extend towards the center of the wheel ten uniformly distributed bulges 24 shaped so that at a motion of the slide 20 the pin 22 can be displaced 50 therein in a closely fitting manner. If the pin 22 is in engagement with one of the bulges 24, it will drive the tens wheel 10a when the unit wheel 9 is fed, this driving taking place, however, not to the extent of a full revolution but merely for 55 a single feeding step of the unit wheel as is necessary of course in the circumstances. Engagement of the pin 22 with one of the bulges 24 is effected by causing, at a corresponding position of the unit wheel 9, the projecting end of the 60 slide 20 during depression of the wheel 6 carrying the number wheels to strike a stop 25 provided on the base plate 1a of the frame 1, and to be pressed back. If at this position of the slide 20 the unit wheel 9 is rotated by the pawl 18, the tens wheel 65 10a, as stated, will be driven also, the outer edge of the slide pin 22 sliding along the stop 25. As the feeding of the unit wheel 9 by means of the pawl 18 is effected while the shaft 6 rises again, 70 the bulges 24 must be so deep that the pin 22

remains therein almost during the entire feed motion.

When the unit wheel 9 is fed forward by the pawl 18, the transition to the tens, i. e., the driving of the tens wheel 10a by the pin 22, must take 5 place at the time the figure 9 of the unit wheel 9 is in printing position. On the other hand, if the unit wheel 9 is fed backward by the pawl 18, driving of the tens wheel is effected when the figure 0 is in printing position on the unit wheel 10a. As in the first case the member 22 is in a different position relative to the base plate 1a of the frame 1 than in the second, the stop 25 initiating the driving of the tens wheel 10a must be capable of occupying different positions on the 10 plate 1a according to whether the pawl 18 is set for forward or backward feed. For this reason the stop 25 is disposed on a slide 26 movable in a transverse groove of the base plate or web 1a of the frame 1 and adapted to be brought into 15 two end positions, according to whether the pawl 18 is secured to the one or other lever 15.

On the underside of the shaft 6 a longitudinal groove 6a is provided from which transverse bores 6b extend closely in front of the wheels 10a, 10b, etc. Into the transverse bores 6b one end of angular sheet metal pieces 27 is introduced whose other side is inserted in the longitudinal groove 6a. The wheels 10a, 10b, etc. are provided in their bores with ten grooves, and if they are 25 in printing position, one of these grooves is located directly underneath a metal piece 27. The metal pieces 27 are subjected to the action of springs 28 disposed in bores of the shaft 6 for pressing the side of the metal piece 27 parallel 30 to the shaft 6 into the opposite groove of the respective number wheels 10a, etc. which are thus secured in their position occupied at the time. The unit wheel 9 and the tens wheel 10a are now 35 so close together that the angular member 27 engages with its free end a corresponding groove 40 of the slide 20 arranged on the unit wheel 9. When the slide 20 is pushed back on coming in contact with the stop 25, it simultaneously acts upon the angular member 27 locking the tens 45 wheel 10a and depresses it until it is disengaged from the wheel 10a which is thus released for feeding. When the slide 20 returns to initial 50 position after disengagement from the stop 25, the angular member 27 will engage again a groove 55 of the tens wheel 10a to lock this wheel with the shaft 6. The lower edge of the angular member 27 and the grooves of the tens wheel 10a are wedge-shaped, so that the wheel 10a is always drawn into a definite position, owing to the wedge effect of the angular member 27 and the grooves. This automatic positioning of the tens wheel 10a is important for the reason that it is necessary for the slide 20 to leave the stop 25 just before the feeding of the unit wheel 9 is completed to 60 prevent the slide 20 at the next depression of the shaft 6 when the tens wheel 10a need not be fed from coming with its rear end in contact with the stop 25.

Feeding of the hundreds, thousands, etc. is like 65 feeding the tens. For this purpose, each wheel 10b, 10c, etc. is provided on one side with a slide 20 fitted with a pin 22 and on the other side a concentric annular groove 23 having bulges 24. There is further provided a stop 25 for each wheel, 70 these stops being absolutely alike and arranged on the common carriage 26. As the stops 25 as well as all other parts required for the feeding of tens are of similar construction within their type, automatic feeding can be provided for each num- 75

ber wheel, whereas in the known numbering apparatus employing pawl sets of constantly decreasing size automatic feeding is possible only up to the thousands wheel and higher figure 5 wheels have to be actuated by hand.

It is evident that feeding of the number wheels cannot be effected as long as they are in contact with the work to be printed, as otherwise blurring of the freshly printed figures would result. For 10 this reason, means are provided for retarding the feeding motion until the numbers are again at a sufficient distance from the sheet on which a figure has just been printed. The essential part of this retarding device is a feeler lever 29 mov- 15 ably disposed on one end of the shaft 6 and half inserted in one of the hollow sides 1b of the frame 1, the other half of it projecting outwardly through a slot in the plate 2 covering this hollow space. The portion of the feeler 29 located inside the 20 hollow space is influenced by a spring 30 which usually keeps it in an almost horizontal position while the exposed end rests laterally on the side 1b of the frame 1. In this position the lever 29 is located somewhat below the vertex of the num- 25 ber wheels 9, 10a, etc., that is, below printing height. When the number wheels are depressed together with the shaft 6, the lever 29 will slightly move up from its horizontal position, as its fulcrum is drawn down with the shaft 6 and its 30 upper portion cannot cooperate in the descent for the reason that it rests on the side 1b of the frame 1. Notwithstanding the downward motion of the lever 29, its outer end will rise to a certain extent, i. e., up to the level of the apex of 35 the depressed number wheels. On the edge of the feeler 29 which is on top when the latter is approximately in horizontal position a clearance 29a forms a notch into which snaps an elastic pawl 31 rotatably disposed on the inside of the 40 wall 3 shutting off the hollow space of the side 1b of the frame 1 when the lever 29 moves down and is simultaneously rotated. If pressure on the number wheels 9, 10a, etc. ceases and the shaft 6 with the number wheels moves up again 45 under the influence of the springs 8, the feeler lever 29 held by the pawl 31 will turn still farther until the pawl 31 automatically slides off from the tooth formed by the notch 29a and releases the lever. During this farther stroke, the lever 50 29 will move beyond the apex of the number wheels and hug the freshly printed sheet or the impression cylinder of the press, so that its further motion depends on the increase of the distance between the impression cylinder and the 55 numbering device. At a complete stroke of the lever 29 due to the pawl 31 the extreme end of the lever will, however, advance ahead of the upward motion of the shaft 6, and the feeding of the number wheels can thus be effected only if 60 the sheet has moved away from them for a certain distance, so that blurring is prevented.

I claim:

1. An automatic numbering device for printing presses, comprising, in combination, a frame, a shaft extending longitudinally through said frame, spring bearings in said frame for said shaft permitting the latter to be depressed by the impression cylinder or platen of a press, a plurality of number wheels on said shaft, a hublike 65 projection on each wheel except the last one on the side facing the next higher number wheel, a spring-actuated radially displaceable slide in said projection, said slide extending with its outer end beyond said projection, a pin carried 70 by said slide, a concentric annular groove in each 75

number wheel except the first on the side facing the preceding number wheel for guiding the pin of the slide of the preceding number wheel, uniformly distributed bulges extending from the inner edge of each annular groove towards the center of the wheel, and a stop at the bottom of the frame under each number wheel for pressing back the slide during the descent of the shaft to cause the pin thereof to engage the annular groove of the adjacent number wheel and to couple both wheels. 5

2. An automatic numbering device for printing presses, comprising, in combination, a frame, a shaft extending longitudinally through said frame, spring bearings in said frame for said shaft permitting the latter to be depressed by the impression cylinder or platen of a press, a plurality of number wheels on said shaft, a hublike projection on each wheel except the last on the side facing the next higher number wheel, a spring-actuated radially displaceable slide in said projection, said slide extending with its outer end beyond said projection, a pin carried by said slide, a concentric annular groove in each number wheel except the first on the side facing the preceding number wheel for guiding the pin of the slide thereof, uniformly distributed bulges extending from the inner edge of each annular groove towards the center of the wheel, a stop at the bottom of the frame under each number wheel for pressing back the slide during the descent of the shaft to cause engagement of the pin thereof with the annular groove of the adjacent number wheel and the coupling of both wheels, and a slide movably disposed within the frame 20 and carrying said stops. 25

3. An automatic numbering device for printing presses, comprising, in combination, a frame, a grooved shaft extending longitudinally through said frame, spring bearings in said frame for said shaft to permit the latter to be depressed by the impression cylinder or platen of a press, a plurality of grooved number wheels on said shaft, a hublike projection on each wheel except the last on the side facing the next higher number wheel, a spring-actuated radially displaceable slide disposed in said projection, a pin carried by said slide, a concentric annular groove in each number wheel except the first on the side facing the preceding number wheel to guide the pin thereof, uniformly distributed bulges extending from each annular groove to the wheel center, a stop at the bottom of the frame under each wheel to engage the slide, another slide movably disposed in the frame for carrying the stops, and an angular member repressibly disposed in the groove of the shaft and engaging a groove of the number wheels and controlled by the stop of the preceding number wheel. 40 45 50 55

4. An automatic numbering device for printing presses, comprising, in combination, a frame, a grooved shaft extending longitudinally through said frame, spring bearings in said frame for said shaft to permit the latter to be depressed by the impression cylinder or platen of a press, a plurality of grooved number wheels on said shaft, a hublike projection on each wheel except the last on the side facing the next higher number wheel, a spring-actuated radially displaceable slide in said projection, a pin carried by said slide, a concentric annular groove in each number wheel except the first on the side facing the preceding number wheel to guide the pin thereof, uniformly distributed bulges extending from each annu- 60 65 70 75

lar groove to the wheel center, a stop at the bottom of the frame under each wheel to engage the slide, another slide movably disposed in the frame for carrying the stops, and an angular member 5 repressibly disposed in the groove of the shaft and engaging a groove of the number wheels and controlled by the stop of the preceding number wheel, said angular member having an arm vertically disposed thereto and guided in a bore of 10 the shaft.

5. An automatic numbering device for printing presses, comprising, in combination, a frame, a grooved shaft extending longitudinally through said frame and elastically arranged in said frame 15 to be depressed by the impression cylinder or platen of a press, a plurality of grooved number wheels on said shaft, a hublike projection on each wheel except the last on the side facing the next higher number wheel, a spring-actuated grooved 20 slide radially displaceable in said projection, a pin carried by said slide, a concentric annular groove in each number wheel except the first on the side facing the preceding number wheel to guide the pin thereof, uniformly distributed 25 bulges extending from each annular groove to the wheel center, a stop at the bottom of the frame under each wheel to engage the slide, another slide movably disposed in the frame for carrying the stops, and an angular member 30 repressibly disposed in the groove of the shaft and engaging a groove of the number wheels and controlled by the stop of the preceding number wheel, said angular member having an arm extending parallel to the shaft and engaging a 35 groove of the slide of the preceding number wheel.

6. An automatic numbering device for printing presses, comprising, in combination, a frame having hollow sides, a shaft extending longitudinally through said frame and elastically arranged 40 therein to be depressed by the impression cylinder or platen of a press, a feeler lever movably disposed at one end of said shaft and partly inserted in one of the hollow sides of the frame, 45 said lever having a notched top edge, a spring for keeping the inserted portion of said lever approximately horizontal, and a spring-actuated pawl rotatably disposed on the frame and adapted to engage the notched edge of said lever 50 during depression of the shaft and to raise the lever during the subsequent ascent of the shaft while being disengaged therefrom.

7. An automatic numbering device for printing presses comprising, in combination, a frame, a shaft extending longitudinally of said frame, 55 a plurality of number printing wheels carried by the shaft and being feedable clockwise or counterclockwise, means for locking the wheels in their occasional positions, means for stepwise feeding said wheels in predetermined order and means adapted to be depressed by the impression cylinder or platen of a press and controlling 60 said wheel feeding means, the part of the wheel feeding means, which is moved by the last named means being arrangeable in two different positions for entailing alternatively a clockwise or a counterclockwise feeding of the number printing 65 wheels.

8. An automatic numbering device for printing presses, comprising in combination, a frame, a shaft extending longitudinally of said frame, a plurality of number printing discs carried by the shaft, a ratchet wheel connected with the unit wheel and being feedable clockwise or counterclockwise, means for locking the wheels in 70

their occasional positions, means for coupling each number printing disc having completed a full revolution with the adjacent number printing disc for the next feeding step, a ratchet pawl engageable with said ratchet wheel, means for 5 actuating said coupling means and means adapted to be depressed by the impression cylinder or platen of a press and controlling said pawl, this pawl being arrangeable in two different positions for entailing alternatively a clockwise or 10 a counterclockwise feeding of the number printing discs.

9. An automatic numbering device for printing presses, comprising, in combination, a frame, a shaft extending longitudinally of said frame, a 15 plurality of number printing discs, carried by the shaft, pins arranged in a concentric circle on the outside of the unit disc, means for locking the wheels in their occasional positions, means for coupling each number printing disc having 20 completed a full revolution with the adjacent number disc for the next feeding step, a ratchet pawl engageable with said circle of pins, means for actuating said coupling means and means adapted to be depressed by the impression cylinder or platen of a press and controlling said pawl, this pawl being arrangeable in two different 25 positions for entailing alternatively a clockwise or a counterclockwise feeding of the number printing discs.

10. An automatic numbering device for printing presses, comprising, in combination, a frame, a shaft extending longitudinally of said frame, a plurality of number printing wheels carried by the shaft, pins arranged in a concentric circle 35 on the outside of the unit wheel, a ball pressed by a spring against said circle of pins, means for coupling each number printing wheel having completed a full revolution with the adjacent number printing wheel for the next feeding step, 40 a ratchet pawl engageable with said circle of pins, means for actuating said coupling means, means adapted to be depressed by the impression cylinder or platen of a press and controlling said pawl, this pawl being arrangeable in two 45 different positions for entailing alternatively a clockwise or a counterclockwise feeding of the number printing wheels.

11. An automatic numbering device for printing presses, comprising, in combination, a frame, 50 a shaft extending longitudinally of said frame, spring bearings in said frame for said shaft permitting the latter to be depressed by the impression cylinder or platen of a press, a plurality of number printing wheels carried by the shaft 55 and being feedable clockwise and counterclockwise, means for locking the wheels in their occasional positions, means for stepwise feeding said wheels in predetermined order, a finger arranged on said shaft and controlling said wheel feeding means, the part of the wheel feeding means which is moved by the finger being arrangeable in two different positions for entailing 60 alternatively a clockwise or a counterclockwise feeding of the number printing wheels.

12. An automatic numbering device for printing presses, comprising, in combination, a frame, a shaft extending longitudinally of said frame, spring bearings in said frame for the shaft permitting the latter to be depressed by the impression cylinder or platen of a press, a plurality of number printing wheels carried by said shaft and being feedable clockwise and counterclockwise, 70 means for locking the wheels in their occasional positions, means for stepwise feeding said wheels 75

in predetermined order, a finger arranged on the shaft and two levers oscillatorily mounted on said frame and adapted to be contrarily actuated by the moving of said finger, and means arrangeable alternatively on the end of one or the other lever for stepwise feeding said number printing wheels in predetermined order clockwise or counterclockwise.

13. An automatic numbering device for printing presses comprising in combination a frame, a shaft extending longitudinally of said frame, spring bearings in said frame for the shaft permitting the latter to be depressed by the impression cylinder or platen of a press, a plurality of

number printing wheels carried by said shaft and being feedable clockwise or counterclockwise, means for locking the wheels in their occasional positions, means for stepwise feeding said wheels in predetermined order, a finger arranged on the shaft and two levers being in alinement oscillatorily mounted on said frame, vertical to the finger and engaging with their ends neighboured with one another, a pin on the finger of said shaft, a ratchet pawl arrangeable alternatively on the outer end of one or the other of the two levers for entailing a clockwise or counterclockwise feeding of the number printing wheels.

KURT FRENZEL.
